(57) **CLAIM**

The ornamental design for a chair, as shown and described.

DESCRIPTION

FIG. 1 is a top, front, left-hand side perspective view of a chair embodying the principles of my new design;

FIG. 2 is a top, rear left-hand side perspective view thereof;

FIG. 3 is a front view thereof;

FIG. 4 is a rear view thereof;

FIG. 5 is a side view thereof as seen from the left-hand side of FIG. 3, the opposite side being a mirror image thereof;

FIG. 6 is a top view thereof; and,

FIG. 7 is a bottom view thereof.

The broken lines shown in the drawings are for the purpose of illustrating portions of the article and form no part of the claimed design.

1 Claim, 7 Drawing Sheets
